UNITED STATES PATENT OFFICE.

AUGUST BALDESBERGER, OF PITTSBURGH, PENNSYLVANIA.

APPARATUS FOR PRESSING AND CREEASING TROUSERS.

Application filed November 28, 1924. Serial No. 752,571.

To all whom it may concern:

Be it known that I, AUGUST BALDESBERGER, a citizen of the United States, residing at Pittsburgh, in the county of Allegheny and

5 State of Pennsylvania, have invented certain new and useful Improvements in Apparatus for Pressing and Creasing Trousers, of which the following is a specification.

My invention relates to an apparatus for 10 pressing and creasing trousers and the primary object of the invention is to provide a conveniently operable device whereby trousers may be properly shaped and creased without the arduous labor attending 15 the pressing operation in the usual manner.

Further objects of the invention are to provide a device of the class stated, in a manner as hereinafter set forth, which is 20 simple in its construction and arrangement, strong, durable and efficient in its use, and comparatively inexpensive to manufacture.

To the accomplishment of these and such other objects as may hereinafter appear, 25 the invention consists of the novel construction, combination and arrangement of parts herein specifically described and illustrated in the accompanying drawing, wherein is shown an embodiment of the invention, but 30 it is to be understood that changes, variations and modifications may be resorted to which come within the scope of the claims hereunto appended.

In the drawing forming a portion of 35 this specification and wherein like numerals of reference designate corresponding parts throughout the several views:—

Figure 1 is a side elevational view of 40 an apparatus for pressing and creasing trousers, in accordance with my invention and in the closed position, with a portion of one of the pressing boards broken away.

Figure 2 is an enlarged side view of a 45 clamp member.

Figure 3 is a sectional view on line III—III, Figure 2.

Figure 4 is an outer end view of the 50 garment supporting clamp.

Figure 5 is a transverse sectional view of 55 a modified construction of a pair of pressing boards.

Referring in detail to the drawing 1 and 2 respectively denote a pair of flat pressing boards which may be constructed from 55 any suitable material. The pressing boards 1 and 2 are connected together at their longi-

tudinal edges by a plurality of hinges 3 so that they may be spread to the open position, or folded together upon each other as shown in Figure 1 of the drawing.

The trousers to be pressed are disposed 60 flatly between the pressing boards 1 and 2 and the latter are then secured in the pressing position by a plurality of substantially U-shaped clamps 4 which overlap the forward edge margins of the pressing boards 1 and 2. Each of the clamps 4 is formed with a projecting apertured ear 5 which is pivotally connected to the pressing board 1 by a pin 6. By this arrangement the clamps 4 may be readily shifted to the engaged position to maintain the pressing boards 1 and 2 in the pressing position or they may be shifted outwardly as shown in dash lines in Figure 1, of 70 the drawing, to disengage the pressing boards 1 and 2 to release the latter. To facilitate the engagement of the clamps 4 with the pressing boards 1 and 2 the free side edges thereof are flared outwardly, as 75 indicated at 7.

The upper marginal edges of the pressing boards 1 and 2 are clamped together 80 with a pair of elongated oppositely disposed garment supporting clamps 8 and 9. Each of the clamps 8 and 9 is substantially U-shaped in transverse cross section and is formed with outwardly flared free side edges 10 for the purpose of facilitating 85 its overlapping engagement with the edges 90 of the pressing boards 1 and 2.

Each of the clamps 8 and 9 is formed 95 with a projecting apertured ear 11 which is pivotally connected to the upper end of the pressing board 1 by means of the pins 12.

The inner end of the ear 11, of the clamp 8, is pivotally connected to the lower end of the toggle bar 13, by a pin 14, and the inner end of the ear 11 of the clamp 9, is pivotally connected to the lower end of the toggle bar 15 by a pin 16. The upper ends of the bars 13 and 15 are pivotally connected together 100 and to the plate 17 by the pivot pin 18. The plate 17 is integrally formed with the ring 19 by which the apparatus is adapted to be suspended.

The connection of the toggle bars 13 and 15 with respective clamps 8 and 9 will allow the latter to be freely and conveniently shifted to the vertical position to release the 105 pressing plates 1 and 2 or to the operative position to engage the latter as shown in

Figure 1, of the drawing. When the apparatus is suspended by the ring 19 the action of the toggle bars 13 and 15 will tend to maintain the respective clamps 8 and 9 in 5 the engaged position during the pressing operation.

When the clamps 8 and 9 are disposed in the operative position they are intended to serve as a hanger element for a coat or any 10 other garment adaptable thereto.

The modified form of pressing boards 1' and 2' shown in Figure 5, of the drawing, differ from those illustrated in connection with the preferred form in that each is 15 constructed with centrally disposed longitudinally extending registering recess 20 whereby a clearance 21 is provided between the boards 1' and 2' when in the pressing position. The clearance 21 is adapted to 20 compensate for the side seams of the trousers and permit of the close engagement of the pressing boards at all other parts of the trousers during the pressing operation.

What I claim is:

25 1. In combination, a device for the purpose set forth comprising a pair of pressing boards, each of said pair of pressing boards having its inner face formed with a centrally disposed longitudinally extending recess, a hinge element connecting the longitudinal edges of one side of said pair of pressing boards together, a plurality of clamping members pivotally connected to one of said pair of boards and shiftable to 30 engage the longitudinal edges of the other side of said pair of boards when the latter are in the folded position, a pair of garment supporting clamps pivotally connected to the upper end of one of said pairs of boards 35 and shiftable to engage the upper edges of said pair of pressing boards, a toggle bar pivotally connected with the inner end of each of said pair of said supporting clamps, and a suspension element pivotally connected with said toggle bars, substantially as described and for the purpose set forth.

40 2. In combination, a device for the purpose set forth comprising a pair of pressing boards, a hinge element connecting the longitudinal edges of one side of said pair

of pressing boards together, a plurality of clamping members pivotally connected to one of said pair of boards and shiftable to engage the longitudinal edges of the other side of said pair of boards when the latter are in the folded position, a pair of garment supporting clamps pivotally connected to the upper end of one of said pair of boards and shiftable to engage the upper edges of said pair of pressing boards, a toggle bar 45 pivotally connected with the inner end of each of said pair of said supporting clamps, and a suspension element pivotally connected with said toggle bars, each of said clamping members and each of said garment supporting clamps being substantially U-shaped in transverse cross section and having its inner side edges flared outwardly substantially as described and for the purpose set forth.

45 3. In combination, a device for the purpose set forth comprising a pair of pressing boards, each of said pair of pressing boards having its inner face formed with a centrally disposed longitudinally extending recess, a hanger element connecting the longitudinal edges of one side of said pair of pressing boards together, a plurality of clamping members pivotally connected to one of said pair of boards and shiftable to 50 engage the longitudinal edges of the other side of said pair of boards when the latter are in the folded position, a pair of garment supporting clamps pivotally connected to the upper end of one of said pairs of boards 55 and shiftable to engage the upper edges of said pair of pressing boards, a toggle bar pivotally connected with the inner end of each of said pair of said supporting clamps, and a suspension element pivotally connected with said toggle bars, each of said clamping members and each of said garment supporting clamps being substantially U-shaped in transverse cross section and having its inner side edges flared outwardly, substantially as described and for the purpose set forth.

55 In testimony whereof I affix my signature.

AUGUST BALDESBERGER.
